(57) CLAIM

The ornamental design for a makeup pen, as shown and described.

DESCRIPTION

FIG. 1 is an upper perspective view of a makeup pen, showing the new design.

FIG. 2 is a front view of the makeup pen of FIG. 1, of which the rear view, left view and right views are the same.

FIG. 3 is an enlarged bottom view of the makeup pen of FIG. 1; and,

FIG. 4 is an enlarged top view of the makeup pen of FIG. 1. In the drawings, the broken lines depict portions of the article that form no part of the claimed design.

1 Claim, 3 Drawing Sheets
